UNITED STATES PATENT OFFICE.

LEON GSCHWIND, OF YOUNGSTOWN, OHIO, ASSIGNOR TO SANITARY SEWER BASIN CO., OF CHICAGO, ILLINOIS.

MANHOLE COVER.

Application filed June 12, 1926. Serial No. 115,527.

The main objects of this invention are to provide an improved manhole cover for street use which effectively retains its position without locking means and one which 5 does not rock or clatter when stepped upon or when a vehicle wheel passes over the same.

Objects relating to details and economies of construction and operation of my invention will definitely appear from the detailed description to follow.

The invention is defined and pointed out in the claims.

A structure which is a preferred embodiment of my invention is illustrated in the accompanying drawing, forming a part of this application, in which:

Fig. 1 is a side elevation of my improved manhole cover, the same being shown as 20 mounted upon a sewer manhole or valve box or the like.

Fig. 2 is a plan view of my improved manhole cover.

Fig. 3 is a vertical section on a line corresponding to line 3-3 of Figs. 1 and 2.

Fig. 4 is a side elevation of the cover proper removed from the body of the manhole.

In the drawing similar reference characters refer to similar parts throughout the several views.

Referring to the drawing, 1 represents the manhole of a sewer, valve box or the like. My improved manhole cover is mounted 35 on the top as is usual practice and comprises an annular body member 2 having a base flange 3 which is set into the pavement of the like with the surface of the pavement flush with the top of the body member.

40 This body member has an internal recess 4 forming a supporting shoulder for the cover 5, the cover having a flange 6 removably fitting the recess.

The supporting shoulder of the body member has a series of inclined steps 7 and 8, the steps 8 having serrations, preferably with rounded edges 9.

45 The cover flange has steps 10 and 11 which correspond to the steps 7 and 8 of the shoulder and fit or rest thereon.

50 A positioning pin 13 projects laterally from the cover to engage the notch 14 in the body member, thus insuring the positioning of the cover with the corresponding 55 steps of the shoulder in proper relation.

The cover is supplied with a handle 15. With the parts thus arranged, the cover is very firmly supported so that it does not rock when stepped upon or a wheel passes over the same, and the serrated edges 8 and 9 tend to wear into a very firm seat. The cover is supported so that it is capable of sustaining very heavy loads.

Having thus described my invention, what I claim as new and desire to secure by Letters Patent, is:

1. In a manhole cover, the combination of an annular body member having an internal annular recess adapted to receive a cover and providing a supporting shoulder therefor, the side wall of the recess being cylindrical, the shoulder having a plurality of inclined steps, certain of which have plain faces and certain of which are serrated, the serrations having relatively blunt curved edges, and a cover having an externally cylindrical flange fitting within said recess in said body member, the lower edge of the flange being stepped to correspond to the steps of its said cover supporting shoulder, 70 certain of the steps of the cover being serrated to coact with the serrated steps of the supporting shoulder, the cover having a laterally projecting positioning pin at one side and the body member having a notch 75 to receive said pin.

2. In a manhole cover, the combination of an annular body member having an internal annular recess adapted to receive a cover and providing a supporting shoulder 90 therefor, the side wall of the recess being cylindrical, the shoulder having a plurality of inclined steps, certain of which have plain faces and certain of which are serrated, and a cover having an externally cylindrical flange fitting within said recess in said body member, the lower edge of the flange being stepped to correspond to the steps of its said cover supporting shoulder, 95 certain of the steps of the cover being serrated to coact with the serrated steps of the supporting shoulder, the cover having a laterally projecting positioning pin at one side and the body member having a notch to receive said pin.

3. In a manhole cover, the combination of an annular body member having an internal annular recess adapted to receive a cover and providing a supporting shoulder therefor, the side wall of the recess being 100 105 110 115

cylindrical, the shoulder having a plurality of inclined steps, and a cover having an externally cylindrical flange fitting within said recess in said body member, the lower edge of the flange being stepped to correspond to the steps of its said cover supporting shoulder, the cover having a laterally projecting positioning pin at one side and the body member having a notch to receive said pin.

4. In a manhole cover, the combination of an annular body member having an internal annular recess adapted to receive a cover and providing a supporting shoulder therefor, the side wall of the recess being cylin-

drical, the shoulder having a plurality of inclined steps, certain of which have plain faces and certain of which are serrated, the serrations having relatively blunt curved edges, and a cover having an externally cylindrical flange fitting within said recess in said body member, the lower edge of the flange being stepped to correspond to the steps of its said cover supporting shoulder, certain of the steps of the cover being serrated to coact with the serrated steps of the supporting shoulder.

In witness whereof I have hereunto set my hand,

LEON GSCHWIND.
